RAILWAY TIE PLATE

Frederick A. Preston, Lake Forest, Ill., assignor, by
mesne assignments, to Poor & Company, a cor-
poration of Delaware

Application June 10, 1935, Serial No. 25,775

7 Claims. (Cl. 238—304)

This invention relates to improvements in a combination structure including a tie plate formed with one or more abutments for resisting lateral movement of a railroad rail and rail retaining means associated with the abutments for retaining the rail on the plate, preferably, though not necessarily, with capacity for vertical movement of the rail base relative to the plate.

The general object of the invention is to provide an improved combination structure of the above character in which the rail base abutment on the tie plate member is grooved, during the rolling of the plate, to provide the top portion of said abutment with a pair of spaced ribs which extend the full length of the abutment; one of said ribs being turned outwardly so as to provide the abutment with substantially a dovetail configuration in cross section adapted to receive, in interlocking engagement, a rail retaining clip member. The invention contemplates broadly, in this connection the provision of suitable construction and arrangements whereby the clip member will be firmly secured in its operative position without requiring engagement between the clip 25 and the rail base and whereby the clip may be applied by movement either lengthwise or transversely of the said abutment.

Another object is to form on a tie plate, a rail base abutment of the above character in which the said ribs diverge from each other toward the middle of the plate, whereby movement of the rail retaining clip longitudinally of the abutment toward the middle of the plate effects a firm wedging engagement of the clip on the said abut- 35 ment.

Other objects of the invention will be apparent from the detailed description of the specific constructions of the invention illustrated in the accompanying drawing, wherein:

Fig. 1 is a plan view of tie plate constructed in accordance with this invention together with a pair of rail retaining clips applied thereon; and

Fig. 2 is a fragmentary sectional view taken on line 2—2 of Fig. 1.

Referring to Figs. 1 and 2 of the drawing, 10 designates the base portion of a railroad rail, 11 a portion of a railroad cross tie, and 12 designates one approved form of a tie plate constructed in accordance with this invention. The tie plate 12 is preferably secured rigidly to the cross tie 11 by means of suitable attaching devices, for example lag screws 13—13. If desired additional fastening devices may be inserted through the apertures 14—14 of the tie plate. The tie plate is 55 formed at opposite sides of the rail seat 15 with

upstanding flanges 16—17 which, preferably, extend across the plate from edge to edge thereof. The inner faces 16a—17a of said flanges are parallel to the longitudinal edges of the rail base and provide lateral abutments for maintaining the rail in proper position on the tie plate. The rail base abutments 16—17 increase in thickness toward the middle of the plate, as shown best in Fig. 1 of the drawing, and are, preferably, somewhat higher than the vertical edge surfaces of 10 the rail base. The top portions of the rail base abutments are formed with grooves 18—19 of uniform width which extend the full length of the abutments and provide spaced ribs 20—21. The inner rib 20 of each abutment is parallel to the 15 inner face thereof, but the outer rib 21, by reason of the unequal displacement of metal in forming the adjacent groove, assumes a tapered configuration. With this construction the outer surface of the rib 21 diverges from the inner rib 20 and 20 thereby forms a wedge surface which increases in thickness toward the middle of the plate. The rib 21 is also turned outwardly so as to provide the abutment with a substantially dovetail configuration in cross section.

The rail base is retained on the plate by means of clip members 22—22 which are recessed to conform substantially to the cross sectional configuration of the rail base abutments. The central rib portion 23 of the clip extends movably into 30 the groove portion of the rail abutment and the downturned jaws 24—25 of the clip embrace and interlock with the ribs 20—21 of the abutment. The inner surface of jaw 25 is preferably tapered to conform generally to the tapered configuration 35 of the rib 21. The inner jaw 24 may be formed of any suitable length to provide the desired clearance between the jaw and the top surface of the rail base 10.

The retaining clips are applied to their operative positions by driving them longitudinally of the rail abutments until firm wedging engagement is obtained. The interfitting rib and recess construction of the rail abutments and clip members 45 provide gripping surfaces of relatively large area which by their engagement with each other resist retrograde movement of the clips on the abutment members.

While the invention has been illustrated in connection with a tie plate formed with like abutments at opposite sides of a rail base it will be obvious that one of said abutments may be made of different form and that the combination structure may be otherwise modified within the scope 55

of the claims without departing from the spirit of the invention.

I claim:

- 5 1. A tie plate formed on its top surface with a rail base abutment member the top portion of which is formed with ribs disposed in vertically diverging relation to each other, and having outer surfaces which diverge from each other longitudinally of the abutment member, and a clip member movable relative to said abutment member into embracing clamping engagement with said diverging ribs and having a portion overlying an edge of the rail base.
- 10 2. A tie plate provided with a rail seat and at one side of the seat with an upstanding rail base abutment the top of which is grooved to provide spaced ribs which diverge from each other longitudinally of the abutment, and a rail retaining clip member provided with a portion extending into said groove and with jaws embracing said ribs and movable into tight interlocking engagement therewith.
- 15 3. A tie plate provided with a rail seat and at one side of the seat with an upstanding rail base abutment extending across the plate and increasing in thickness toward the middle of the plate; the top of the abutment being grooved to provide spaced ribs which diverge from each other toward the middle of the plate; and a rail retaining clip member provided with jaws for embracing said ribs and adapted to be driven longitudinally of said abutment into wedging engagement with said ribs.
- 20 4. A tie plate provided with a rail seat and at one side of the seat with an upstanding rail base abutment extending across the plate and increasing in thickness toward the middle of the plate, the top of the abutment being grooved to provide spaced ribs which diverge from each other toward the middle of the plate, and a rail retaining clip member recessed to conform substan-

tially to the cross sectional contour of the upper portion of said abutment and adapted to be driven longitudinally thereof into wedging engagement with said ribs.

5 5. A tie plate provided with a rail seat and at one side of the seat with an upstanding rail base abutment extending across the plate and increasing in thickness toward the middle of the plate, the top of the abutment being grooved to provide a rib parallel with the inner face of the abutment and an outturned rib substantially parallel with the outer face of the abutment, and a rail retaining clip member recessed to conform substantially to the cross sectional contour of said groove and ribs and adapted to be driven 10 lengthwise of the abutment into wedging engagement therewith.

6. A tie plate provided with a rail seat and with upstanding abutments extending across the plate at opposite sides of said seat, the top portion of each abutment being grooved to provide spaced ribs which diverge from each other toward the middle of the plate, and rail retaining clip members provided with jaws for embracing said ribs and adapted to be driven longitudinally of said 25 abutments into wedging engagement therewith.

7. A tie plate provided with a rail seat and with upstanding rail base abutments extending across the base at opposite sides of said rail seat and increasing in thickness toward the center 30 of the plate, there being a groove in the top of each abutment to provide it with a rib parallel with the inner face of the abutment and with an outturned rib substantially parallel with the outer face of the abutment, and a rail retaining clip 35 member having surfaces for wedging interlocking engagement with said ribs and adapted to be driven longitudinally of the abutment into firm gripping engagement therewith.
